UNITED STATES PATENT OFFICE

101,580

DESIGN FOR A TEXTILE FABRIC OR SIMILAR ARTICLE OF MANUFACTURE

John F. Gaul, Jr., Clifton, N. J., assignor to Botany Worsted Mills, Passaic, N. J., a corporation of New Jersey

Application June 19, 1936, Serial No. 63,390

Term of patent 14 years

To all whom it may concern:

Be it known that I, John F. Gaul, Jr., a citizen of the United States of America, residing at No. 1110 Van Houten Avenue, in the town of Clifton, State of New Jersey, have invented a new, original, and ornamental Design for a Textile Fabric or Similar Article of Manufacture, of which the following is a specification, reference being had to the accompanying drawing, forming a part thereof, and showing a face view of a piece of textile fabric embodying my design.

The characteristic feature of the present design resides in a plain base fabric which is loosely woven, resulting in a rough or crepe-like appearance, series of alternating groups of parallel ribs

composed of threads, the groups of ribs consisting of two threads and four threads alternating in a horizontal direction across the face of the fabric, the relation of the several groups of threads being that two groups of two threads are disposed between groups of four threads, with said spaced threads producing nubs of substantial length at spaced intervals along said threads, the spaces vertically between the nubs produced by said threads being substantially the same.

I claim:

The ornamental design for a textile fabric or similar article of manufacture, substantially as shown and described.

JOHN F. GAUL, JR.
